IGNITION SYSTEM

Samuel G. Eskin, Pittsburgh, Pa., assignor to
 Robertshaw Thermostat Company, Young-
 wood, Pa., a corporation of Pennsylvania

Application October 18, 1940, Serial No. 361,739

13 Claims. (Cl. 175—115)

This invention relates to ignition systems and more particularly to electrical ignition devices for gaseous fuel burners.

Ignition devices of this type include those using an electrically heated coil of wire which is incorporated in a circuit embodying a relay device.

The relay introduces a time delay between the energizing of the ignition coil and the opening of the gas valve in order that the coil may reach igniting temperature before the gas begins to flow. The danger involved in permitting the escape of unburned gas is of common knowledge and it is essential that all contingencies which may subject these devices to this hazard be guarded against.

It thus becomes necessary in approaching this problem to consider not only the customary mode of operation of gaseous fuel burners, but also unusual acts which may prove hazardous if the ignition system is not safeguarded in all conceivable ways. The principal defect in prior devices of this nature has been that the escape of unburned gas could occur under certain modes of operation of the ignition system. For example, where thermal elements have been utilized in the time delay relay device, there has often been insufficient time between turning the ignition on, then off, then on again for this element to regain its original position and prevent the gas valve from opening before the ignition coil reaches ignition temperature upon the final operation.

Another problem to be considered in devices of this character is that the ignition system is invariably subjected to the ambient temperatures of the fuel burner. Time delay relay devices are often of a type which change their timing if exposed to variations in ambient temperature. Hence, unless compensation, with its attendant expense and complication, is added to such devices, they cannot operate satisfactorily under ordinary conditions.

An object of this invention is to ensure safe and dependable operation of an electric ignition system for gaseous fuel burners.

Another object of the invention is to forestall opening of the gas valve under any conditions until the ignition coil has reached ignition temperature.

Another object of the invention is to reduce the time delay between energization of the ignition coil and opening of the gas valve to the minimum consistent with safety.

Another object of the invention is to render the operation of the device unaffected by ambient temperatures without introducing compensating means.

Another object of the invention is to prevent continued flow of gas upon failure of the electric circuit or power supply to the ignition system.

Another object of the invention is to reduce the heat added by the ignition coil to an oven or the like where the fuel burner may be located.

Another object of the invention is to permit the use of expensive materials for the ignition coil without adding materially to the initial cost of this element or to the cost of replacement.

Another object of the invention is to operate the system on a voltage which will ensure satisfactory switching.

Another object of the invention is to construct the device of a simple, compact and rugged design which will render it inexpensive to manufacture and reliable in operation.

Other objects and advantages will become apparent from the following description taken in connection with the accompanying drawing wherein is shown a diagrammatic view of an ignition system embodying this invention.

Referring more particularly to the drawing, an oven compartment 10 of a gas range is shown 25 as having the usual gas burner 12 supported therein. In this instance, the flow of gas to the burner 12 is under control of a thermostatic regulator 14 which is interposed between the gas inlet 16 and the burner 12. The regulator 14 also embodies a main gas cock (not shown) having a rotatable operating stem 18 carrying the dial 20 and by means of which the inlet 16 may be opened and closed in the usual manner. The thermostatic control of the oven 10 is completed by the provision of the thermal element 22 supported in 35 the oven and operatively connected to the regulator 14. As such controls are well-known and form no part of the present invention, further description is deemed unnecessary.

A solenoid gas valve 24 of any known type is 40 interposed in the gas inlet line preferably between the regulator 14 and the burner 12. Such valves may be arranged, as in this instance, to be opened by energization of the solenoid and closed by gravity as is well known. A wire 26 connects

45 the solenoid gas valve 24 to one terminal of a main switch 28 shown as supported by the regulator 14 adjacent the gas cock stem 18. Operation of the main switch 28 may be effected by a cam 29 carried on the stem 18 and arranged to 50 close the switch when the gas cock is rotated to open position. It will be understood that the thermostatic control could be omitted, leaving the main switch operable upon rotation of the gas cock, or separately operable if desired. The 55 other terminal of the main switch 28 is connected

by a wire 30 with the secondary of a transformer 32, the primary of which is connected to the power line. The secondary supplies current by way of a wire 34 to a resistor 36 which is connected by wire 38 to an ignition coil 40. A wire 42 connects ignition coil 40 to the solenoid gas valve 24. Hence, the solenoid gas valve, ignition coil and resistor are in series with the transformer as shown schematically in the drawing.

The component parts described thus briefly are, in themselves, subject to modification or, in some cases, may be omitted from the assembly. The transformer 32 in the embodiment described is designed for use where current of 115 or 220 volts is supplied to the power line. The transformer permits operation of the system at a suitable low voltage, such as for instance, 12 volts. The resistor 36 limits the current flow to the ignition coil 40 allowing the use of a relatively short coil. While the resistor 36 is shown as being a wire or ribbon type, it will be apparent that a lamp, or a combination lamp and coil, may be substituted.

The ignition coil 40 is located in proximate relation to the burner 12 which it is designed to ignite. Preferably, only the ignition coil 40 and the burner 12 of this assembly are housed within the oven 10 of the gas range when used in such relation, or in the combustion chamber of other devices.

This invention is particularly directed to the provision of means for delaying the admission of gas to the burner until the ignition coil has had sufficient time to reach igniting temperature. To this end, a control relay having a time delay period is incorporated in the ignition system. As shown more or less schematically in the drawing, this control relay may comprise broadly a mercury switch 44, movable between open and closed positions, and an electromagnetic actuator 46 therefor in shunt with the circuit of the solenoid gas valve. The mercury switch may have one terminal connected by a wire 48 to the wire 26 and the other terminal connected by a wire 50 to the wire 42. The electromagnetic actuator 46 has one terminal connected by a wire 52 to the wire 26 and the other terminal of the actuator is connected by a wire 54 to the wire 34.

The mercury switch 44 may be pivotally supported at 56 on a bracket 58 secured to a panel 60. The pivotal support 56 extends through the bracket and further serves as a pivotal connection for the armature 62 of the electromagnetic actuator 46. The mercury switch may thus be tilted from one position to another to open and close the circuit. The mercury is adapted to flow freely when the switch is tilted to close the circuit instantaneously, but is restricted in flowing to open the circuit for a predetermined period of time. In the embodiment shown the switch is normally closed, but it will be apparent that the closed position could be intermediate two open positions if desired. Devices of this character are well known in the art and many modifications could be made in the structure which has been described for illustrative purposes only. It will further be apparent that the invention is not limited to the use of a control relay embodying a mercury switch as other types of relay fulfilling the objects of the invention could be used as explained hereinafter.

In the operation of the ignition system described, the closing of the main switch 28 establishes a circuit to one side of the electromagnetic actuator 46 through the wire 38, transformer 32,

wire 34, and wire 54. The circuit back to the main switch 28 is completed by the wire 52 and wire 26 as described. Immediately upon energization of the actuator 46, the mercury switch 44 is tilted into the restricted flow position but the switch remains closed until the desired time delay period expires. Coincident with the energization of the actuator 46, the current also flows through resistor 36, and the ignition coil 40.

Due to the mercury switch 44 being connected in shunt with the solenoid gas valve 24 by wires 48 and 50, the solenoid coil is shorted out and the gas valve remains closed as long as the mercury switch is closed. The shunt, however, permits the circuit through the ignition coil to be completed through wire 26 to the main switch 28. Hence, while the mercury switch remains closed and the solenoid gas valve is also closed, the ignition coil is energized to reach igniting temperature. As soon as the time delay period expires, the circuit through the mercury switch opens and the current flows through the solenoid gas valve 24 to open it and permit gas to flow to the burner 12. The ignition coil having at this time reached igniting temperature, the gas flowing from the burner 12 is readily ignited thereby.

It will be apparent that the mercury switch 30 can be arranged to remain closed after tilting for any predetermined period of time. Satisfactory results have been obtained with a delay period of fifteen or twenty seconds during which the ignition coil reaches igniting temperature. 35 The important feature of the device is that there is an immediate resetting of the switch to closed position and a subsequent time delay period whenever the current is switched off or otherwise discontinued through the energizing circuit 40 of the ignition coil. Hence, what may be termed an immediately recycling ignition system is provided.

It will be apparent that in the use of this system there are a number of safety features which are highly desirable. In the first place, it is impossible to create a flow of gas to the burner unless the ignition coil is at igniting temperature. It will be apparent that when the dial 20 is rotated to open the gas cock, thus closing the switch 28, the solenoid gas valve 24 will remain closed until the time delay period has expired. It is only after this predetermined interval has elapsed that the gas can flow to the burner. At such time, as stated, the ignition coil is at igniting temperature.

The invention also protects against unusual operation of the dial which, if not guarded against, would permit the gas to flow before the ignition coil could reach sufficient temperature to ignite it. It will be remembered that the mercury switch is immediately recycling and thus fulfills a useful function. Should the dial 20 be rotated from the open position described to closed position, the main switch 28 will then be opened again. However, the mercury switch is automatically tilted to its initial position and immediately closed due to its instant response in this position. The ignition coil then begins to cool due to deenergization of its circuit. Now should the operator again rotate the dial to open the main gas cock and close the main switch, the usual time delay period must necessarily occur before the solenoid gas valve is energized to permit gas to flow to the burner. Thus, regardless of the temperature of the ignition coil, the immediate

recycling feature of the control relay will always ensure the predetermined delay period whenever the main switch is opened.

A further safety feature of the device is the constantly energized ignition coil. Should the gas be turned off at any point beyond the main gas cock, there is no interference with the electrical circuit to the ignition coil. Thus, as the ignition coil remains at igniting temperature it is always ready to ignite the gas as soon as it is again turned on.

It is apparent, moreover, that failure of the electrical circuit at any point in the system will result in immediate deenergization of the solenoid gas valve and its closure by gravity. No gas can flow to the burner while the circuit of the ignition coil remains deenergized or when the shunt ceases to function.

The resistor 36 serves a useful purpose in making the operation of the ignition coil possible on any suitable voltage, such as six or twelve volts. The ignition coil can thus be made of a short piece of wire which also serves a useful purpose in permitting more efficient, but more expensive, materials to be used for this element. Moreover, the heat added to the oven compartment is reduced to a minimum by reducing the size of the ignition coil and locating the resistor outside. As modern gas ovens are designed to operate under low temperatures, the elimination of undue added heat is an important advantage.

The preferred form of control relay has been described as embodying a mercury switch. Such devices are unaffected by ambient temperatures which may be as high as 300 degrees F. at the point of mounting on the range. Due to this feature there is no change in the timing of the relay which otherwise would require compensation. It will be understood, however, that the invention is not limited to the preferred form described, but that other suitable component parts may be substituted if desired.

The various modifications which can be made in the details of construction and arrangement of parts will be apparent to those skilled in the art, and can be made without departing from the spirit of the invention. In particular, any suitable type of control relay having the time delayed operation and recycling features can be employed. Any type of resistor, including a signal lamp, can be substituted for the resistor described. Also, any suitable type of burner requiring ignition can be used in conjunction with this system as well as the gas range type shown. Reference is, therefore, to be had to the appended claims as defining the scope of this invention.

I claim:

1. An electric ignition device for fuel burners comprising in combination, an electrically operated valve for controlling the flow of fuel to said burner, an electric igniter adjacent the burner for igniting said fuel, means for energizing said igniter and valve, and automatic time delay means for shunting said valve, said time delay means being adapted to delay opening said valve until the igniter reaches igniting temperature and to be reset for such delayed opening immediately upon deenergization of said energizing means.

2. An electric ignition device for gaseous fuel burners comprising in combination, a solenoid fuel valve, an electric ignition coil in the energizing circuit of said solenoid fuel valve, and a control relay comprising a switch for shunting said valve, said relay being adapted to delay opening said valve until the coil reaches igniting tem-

perature and to be reset for such delayed opening immediately upon said circuit becoming deenergized.

3. An electric ignition device for gaseous fuel burners comprising in combination, a solenoid fuel valve, an electric ignition coil in the energizing circuit of said solenoid fuel valve, and a control relay for shunting said valve, said relay comprising a switch having time-delayed movement to open position and immediate movement to closed position, said time delayed movement permitting the coil to reach igniting temperature before the fuel valve opens, and means for actuating said switch to either of said positions.

15 4. An electric ignition device for gaseous fuel burners comprising in combination, a solenoid fuel valve, an electric ignition coil in the energizing circuit of said solenoid fuel valve, and a control relay for shunting said valve, said relay comprising a mercury switch occupying a closed position when said circuit is deenergized, said switch having time-delayed movement to open position permitting the coil to reach igniting temperature before the fuel valve opens.

20 5. An electric ignition device for gaseous fuel burners comprising in combination, a solenoid fuel valve, an electric ignition coil in the energizing circuit of said solenoid fuel valve, and a control relay for shunting said valve, said relay comprising a mercury switch occupying a closed position when said circuit is deenergized, said switch having time-delayed movement to open position and being immediately reset for such movement in the closed position, said time-delayed movement permitting the coil to reach igniting temperature before the fuel valve opens, and means for actuating said switch to either of said positions.

25 6. An electric ignition device for gaseous fuel burners comprising in combination, a solenoid fuel valve, an electric ignition coil in the energizing circuit of said solenoid fuel valve, and a control relay for shunting said valve, said relay comprising a mercury switch occupying a closed position when said circuit is deenergized, said switch having time-delayed movement to open position and being immediately reset for such movement in the closed position, said time-delayed movement permitting the coil to reach igniting temperature before the fuel valve opens, and electromagnetic means for actuating said switch to either of said positions.

30 7. An electric ignition device for gaseous fuel burners comprising in combination, a valve for controlling the flow of fuel to said burner, electromagnetic means for operating said valve between closed and open positions, an electric incandescent igniter adjacent the burner adapted to reach a temperature sufficient for igniting said fuel, a resistor for limiting current flow to said igniter, switching means for connecting said igniter and valve operating means to a source of energizing current, and an electromagnetic relay energized during energization of said igniter and operable for maintaining said valve closed during a predetermined period following energization thereof and adapted to be immediately reset for such delay period upon deenergization thereof, said delay period being fixed solely by said time-delay means and permitting said igniter to reach igniting temperature.

35 8. An electric ignition device for gaseous fuel burners comprising in combination, a solenoid fuel valve, an electric ignition coil in the energizing circuit of said solenoid fuel valve, and a

control relay for shunting said valve, said relay comprising a mercury switch occupying a closed position when said circuit is deenergized, said switch being tilttable upon energization of said circuit to cause opening thereof with time delayed action sufficient to permit the coil to reach igniting temperature before the fuel valve opens, and an electromagnet having an armature connected to said switch for effecting said tilttable movement.

9. An electric ignition device for gaseous fuel burners comprising in combination, a valve for controlling the flow of fuel to said burner, a solenoid for operating said valve between closed and open positions, an electric incandescent igniter adjacent the burner adapted when energized to reach a temperature sufficient for igniting said fuel, an electrical resistance element in the circuit of said igniter, switching means for connecting said igniter and valve solenoid to a source of energizing current, and an electromagnetic relay energized in response to energization of said igniter and operable for maintaining said valve closed irrespective of the temperature of said igniter for a period sufficient for said igniter to reach igniting temperature and being adapted to be immediately reset for such period upon deenergization thereof.

10. An electric ignition device for gas ranges comprising in combination, a gas burner in the oven compartment of said range, a solenoid gas valve for controlling the flow of gas to said burner, an electric ignition coil in the energizing circuit of said gas valve and located in proximate relation with said burner, a resistor located outside said oven compartment and adapted to limit the current flow to said igniter, and a control relay for shunting said gas valve, said relay comprising a mercury switch occupying a closed position when said circuit is deenergized, said switch being tilttable upon energization of said circuit to cause opening thereof with time delayed action sufficient to permit the coil to reach igniting temperature before the gas valve opens and being immediately reset for such movement when said

circuit is deenergized, and an electromagnet having an armature connected to said switch for effecting said tilttable movement.

11. An electric ignition device for gaseous fuel burners comprising in combination, electrically operated means for controlling the flow of fuel to said burner, electric igniting means for said burner in series circuit with said controlling means, means for energizing said igniting and controlling means, and a control relay having a timing element connected in parallel circuit with said controlling means and operable to delay energization of said controlling means until the igniting means reaches igniting temperature.

15 12. An electric ignition device for gaseous fuel burners comprising in combination, electrically operated means for controlling the flow of fuel to said burner, electric igniting means for said burner in series circuit with said controlling means, means for energizing said igniting and controlling means, and a control relay for delaying energization of said controlling means until the igniting means reaches igniting temperature, said relay comprising a coil connected in parallel with said controlling and igniting means and adapted to operate a time delay switch connected in parallel with said controlling means only.

20 13. An electric ignition device for fuel burners having means for supplying fuel thereto comprising an electric igniter, electrically operable means energizable for actuation to a position for admitting fuel to the burner, a main switch operable for causing energization of a circuit including said igniter and fuel admitting means, 25 and a control relay electrically connected to said fuel admitting means for causing said means to remain unactuated for a predetermined period following energization of said circuit, said relay including an initially closed switch which opens 30 after a time delay period following energization of said circuit and resets for such delay period substantially instantaneously upon deenergization of said circuit.

SAMUEL G. ESKIN.
